UNITED STATES PATENT OFFICE

2,448,350

LADDER BRACKET

Cecil L. Brown, Chattanooga, Tenn.

Application November 24, 1945, Serial No. 630,590

1 Claim. (Cl. 228—61)

1

The present invention relates to new and useful improvements in ladders, and more particularly to a bracket mounted on the ladder and adapted to support the ladder outwardly in spaced relation from the edge of a roof to prevent injury to the gutter or eaves and also to provide means whereby scaffolding or platforms may be supported on the ladder.

An important object of the present invention is to provide a ladder bracket of this character embodying means for securing the bracket in vertically adjusted position on the side rails of the conventional form of ladder and including inwardly projecting arms having roof-engaging shoes pivotally mounted thereon and adapted to rest upon a roof to support the ladder in spaced relation from the edge of the roof, to thus protect the eaves or gutter from injury by the ladder.

A still further object is to provide a device of this character of simple and practical construction which may be easily and quickly applied to a ladder of conventional construction without the necessity of making any changes or alterations therein, and at the same time embodies a strong and safe construction which is relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a side elevational view,

Figure 2 is a top plan view, with the bracket arms removed,

Figure 3 is a sectional view taken substantially on a line 3—3 of Figure 1,

Figure 4 is a side elevational view of one of the locking wedges with parts broken away and shown in section,

Figure 5 is a fragmentary rear elevational view,

Figure 6 is an enlarged front elevational view of one of the bracket arms,

Figure 7 is a top plan view of one of the slides for mounting the bracket on the rail of a ladder,

Figure 8 is a view in elevation of the guides for one of the braces of the bracket arm,

Figure 9 is a perspective view of one of the pivoted roof-engaging shoes, and

Figure 10 is a longitudinal sectional view thereof.

Figure 11 is a fragmentary view in side elevation illustrating the use of the invention as a support for scaffolding.

Referring now to the drawings in detail, where-

2

in, for the purpose of illustration, I have disclosed a preferred embodiment of the invention, the numerals 5 and 6 designate a pair of channel-shaped slides adapted for slidably mounting on the rails 7 and 8, respectively, of a conventional form of ladder, the slides being connected to each other at their rear edges behind the rails by means of a plurality of transversely extending, vertically spaced slats 9.

10 A channel-shaped socket member 10 is welded or otherwise suitably secured to the slides 5 and 6, or integrally formed therewith, if desired, and extends vertically on the outer side of each of the rails 6 and 7.

15 A brace 11 constructed of flat sheet metal includes a vertical portion 12 slidably mounted in the socket 10, and a horizontal portion 13 which projects outwardly at the side of the ladder.

20 A bracket arm 14 has its lower end welded or otherwise suitably secured to the lower portion of the vertical member 12 of the brace 11 and extends upwardly through an opening 13a at the end of the horizontal portion 13 of the brace in an outwardly inclined direction and terminates in a 25 substantially horizontal, inwardly projecting end portion 15 which terminates behind the ladder.

A shaft 16 extends transversely through the inner end 15 of the arm 14 and on which is pivotally mounted a shoe 17.

30 The shoe 17 is of box-like construction having its top and bottom open and a U-shaped extension 18 at one end in which the end 15 of the arm 14 is inserted.

35 A plate 19 projects horizontally rearwardly from each of the slides 5 and 6 and through the rear portion of which a transversely extending rod 20 is inserted and positioned behind the ladder.

40 A locking dog or wedge 21 is pivotally mounted on the rod 20 immediately behind the respective rails 7 and 8, each of the locking dogs having a curved front edge 22 adapted for movement into and out of frictional wedging engagement with the rear edge of the ladder rails, and connected at their rear edges by a cross bar 23 for uniform 45 swinging movement, the cross bar being provided with an eye 23a each end thereof for attaching a rope 23b to either eye to swing the dogs out of locking position. A coil spring 24 connects the upper edge of the dogs with the rear of the respective slides 5 and 6 to urge the dogs upwardly 50 into their locking position. The rope 23b is designed to be pulled upwardly to swing the locking dogs 21 out of locking position.

55 In the operation of the device, when the bracket is desired to support the ladder in outwardly spaced relation with respect to the gutter 25 at the edge of a roof 26, the slides 5 and 6 are placed over the upper ends of the rails 7 and 8 of the ladder and moved downwardly thereon into a position immediately below the gutter 25 as shown to

advantage in Figure 1 of the drawing. The slides are then locked in position by the dogs 21.

The brackets 11 are then placed in the sockets 10 so that the arms 14 will project rearwardly in a manner so that the shoes 17 at the rear-ends of the arms will lie flatly on the roof 26 and the ladder is thus supported outwardly from the gutter 25 to prevent injury to the gutter.

By placing the braces 13 in the sockets 10 in a position so that the arms 14 project forwardly of the ladder, as shown in Figure 11, the arms may then be used to support scaffolding not shown thereon.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claim.

I claim:

A ladder bracket comprising slides adapted for mounting on the rails of a ladder, pivoted clamp-

ing dogs carried by the slides adapted for movement into and out of clamping engagement with the rails to secure the slides in vertically adjusted position thereon and rigidly connected for movement in unison, a pair of separate arms removably carried by the slides and adapted for positioning at the opposite sides of the ladder to project forwardly or rearwardly therefrom, and shoes removably carried by the arms and adapted to rest upon a roof to space the ladder outwardly from the edge of the roof when the arms are projected rearwardly, said arms being adapted to support scaffolding thereon when projected outwardly.
